JOHN BROWN BAXTER, OF WATERVLIET, NEW YORK, ASSIGNOR TO COVERT MANUFACTURING CO., OF WATERVLIET, NEW YORK, A CORPORATION OF NEW YORK.

SNAP-HOOK.

1,276,008.

Specification of Letters Patent. Patented Aug. 20, 1918.

Application filed May 16, 1917. Serial No. 169,088.

To all whom it may concern:

Be it known that I, JOHN B. BAXTER, citizen of the United States, residing at Watervliet, in the county of Albany and State 5 of New York, have invented certain new and useful Improvements in Snap-Hooks, of which the following is a specification, reference being had therein to the accompanying drawing.

- 10 This invention relates to improvements in hooks, and more especially that type of hook known in the art as snap hooks, and has for its primary object the provision of an improved construction of eye for the hook enabling the ready attachment thereof while 15 open to the link of a chain or the like and permitting the eye to be relatively permanently closed to similarly confine the link in the eye.
- 20 Heretofore, snap hooks have quite generally been provided with eyes at that end of the shank opposite to the end carrying the snap hook proper, but the formations of the prevalent styles of eyes present marked disadvantages. For example, it has been 25 previously suggested that the eye be formed of overlapping curved members constituting the working end of the eye but such a construction is objectionable because of the 30 weakening of the eye incident to said split formation and because of the relatively weakened nature of the component part of the eye.

An eye formed by casting a hook-like 35 member adapted to remain open until the insertion of the ring or link to which the same is to be attached, and adapted to be hammered or otherwise forced to close the end of the hook on to a seat provided on the shank, has also been employed to considerable extent, but in such devices the metal constituting the working end or bend of the eye is distorted in the sense that the metallic particles are displaced and relatively 40 pressed or separated at different points, resulting in the corresponding weakening of the eye and frequently fracturing if not entirely breaking away portions thereof.

My present invention overcomes the difficulties thus confronting workers in the art 50 and users of snap hooks, as above outlined, the preferred embodiment of the invention embracing the casting of the shank of the snap hook with a fixed hook-like eye portion normally providing an opening into

the same, combined with a closure adapted to bridge the space between the shank and the end of the hook to constitute a relatively permanent element completing the eye without splitting, bending, or displacing the 60 hook portion of the eye, as originally formed, or consequent impairment of the latter in any manner.

I have conceived many embodiments of the invention herein disclosed, each presenting special details in construction and arrangement of parts, but for the sake of illustration in imparting a full understanding of said invention, I will herein illustrate but one convenient and practical embodiment 65 thereof. Upon an examination thereof in connection with the detailed description hereinafter contained, the underlying spirit or principle of the invention will be apparent and the breadth thereof appreciated 70 from the scope of the hereto appended claims.

In the said drawings,

Figure 1 is a face view of a snap hook provided with my present improvements. 80

Fig. 2 is an edge view of the same.

Fig. 3 is a longitudinal sectional view, and,

Fig. 4 is a view similar to Fig. 1 showing the eye closure in its other position. 85

Referring more specifically to the drawings wherein the same reference letters designate identical parts in the several views, A represents the shank of a snap hook, the same being cast in the nature of a barrel. 90 B is the customary hook adapted to be temporarily closed by the bolt C fitted in the barrel and backed by the spring D located in said barrel, the bolt being provided with the customary thumb-engageable projection 95 E, the stem of which moves back and forth in the slotted portion F of the barrel as the bolt is retracted or permitted to be thrust outwardly under the action of its spring. This bolt and associated parts form a relatively temporary closure for the hook because of the facility with which the same may be opened or closed under the actuation of the thumb of the user and without the interpositioning of extraneous implements 100 or devices to retract the bolt.

The opposite end of the shank or barrel A is, similarly to the formation of the hook B therewith, cast integrally with a hook-like eye portion G of solid material and suitable 110

in size to alone constitute the bend or working end of the eye. It is to be observed that the location of the part just described is such that the space H on the interior of the eye is centrally disposed, that is, in line with the longitudinal axis of the shank or barrel A so that the chain or other part to which the eye may be attached will have a straight pull at the bend or working end of the eye 10 correspondingly in line with the shank or barrel; also that the end of the hook-like eye portion terminates at one side of the device but in a plane running parallel to the shank or barrel, said end being sufficiently spaced 15 from the end of the barrel to initially form an opening for the insertion of a chain link, ring, or equivalent device in the eye.

Now, when the snap hook is once attached to the chain or other member intended to 20 carry the snap hook, it is rarely necessary to remove the latter, and I therefore provide a closure for the opening of the eye to which allusion has been made, which closure is of what I have termed a relatively permanent 25 character, that is, one that cannot be opened without difficulty as compared to the snap hook *per se*, or in fact without the use of some implement or device other than the hands of the operator to effect such opening as expediency may require, as in case of 30 breakage to permit the substitution of another in its stead. This closure has a bar J of approximately the size of the hook-like portion of the eye, one end of the bar being 35 reduced to form an apertured ear K to accommodate and overlie an apertured lug L integral with and projecting outwardly from the adjacent side of the shank or barrel A, a pin M passing through the ear and lug 40 pivoting these parts together. It will be seen that the formation and projecting of the lug beyond the side of the shank or barrel disposes the bar when closed in a position parallel to the said shank or barrel 45 and with the opposite end of the bar immediately adjoining the end of the hook-like portion of the shank to bridge the space between the latter and the stem or barrel while enabling the centralizing of the eye 50 before referred to.

The lapping of the pivot end of the bar over the lug to which the same is pivoted reinforces the bar against facewise strains in the direction of the underlying lug, and 55 to strengthen the bar against strains from the opposite direction, the bar is provided with a tongue N at that end which adjoins the end of the hook-like portion of the eye to interfit with a similarly formed tongue O 60 on said end of the hook like portion, all of which is best seen in Fig. 2.

As a means for securely fastening the bar in closed position to perform its function as a barrier across the opening of the eye, 65 said bar is provided with an integral in-

turned hook P adapted to project into the opening of the eye and disposed to have its engaging part face the end of the shank or barrel A so as to engage behind a locking pin Q normally thrust outwardly from the 70 barrel by the bolt spring previously defined, the opposite end of which bolt spring bears against a head R on the locking pin located in the barrel and adapted to contact the end wall S of the latter to limit the outward 75 movement of the locking pin. The end of the inturned hook just referred to is rounded as at T and the outside edge of the end of the locking pin beveled as at U to facilitate the riding of the hook thereover in its 80 closing movement depressing the locking pin, as will be clear.

To prevent inoperative displacement of the locking pin the end of the same is upset or flattened slightly so as to prevent its complete retraction into the relatively smaller aperture V at the end of the barrel through which the locking pin works.

From the foregoing construction it will be appreciated that the eye will originally 90 be opened as indicated by the outwardly swung position of the bar shown in Fig. 4, and upon the engagement of the eye with the chain or member to carry the same the bar may be readily closed under slight pressure to force the same into the position shown in Fig. 1 with the inturned hook latched behind the locking pin. In this position it will be observed that the hook being of somewhat greater width throughout than the size of the locking pin, will protect the locking pin from the ring or chain link in the eye by preventing any endwise engagement with the locking pin, and by the overhanging of the edge walls of the 100 inturned hook with reference to the locking pin the latter is abundantly protected laterally. Thus a relatively permanent fastening is effected. In case of breakage of the hook or for some other reason such as the 110 substitution of another of different size or character, an implement such as the blade of a pen knife may be inserted and by pressure upon the end of the locking pin the same can be forced into the shank or barrel 115 A thereby releasing the inturned hook and permitting the bar to be swung to open position.

Having thus described the invention, what I claim is:

1. A device of the character described comprising a shank provided with an eye including a hook portion carried by the shank, and means for closing the space between the end of the hook portion and the shank including an outwardly-opening bar adjoining, at its opposite ends, adjacent portions of the shank and hook portion, an in-turned part on the bar intermediate the ends of the bar projecting into the eye opening,

- and means interlocking with said inturned part for the purpose described.
2. A device of the character described comprising a shank provided with an eye 5 including a hook portion carried by the shank, and means for closing the space between the end of the hook portion and the shank including an outwardly-opening bar pivoted at one end to the shank and at its 10 other end adjoining the end of the hook portion, and an inturned hook on the bar projecting laterally into the eye opening adapted to interlock with a part carried by the shank for the purpose described.
- 15 3. A device of the character described comprising a shank provided with an eye including a hook portion carried by the shank, and means for closing the space between the end of the hook portion and the 20 shank including an outwardly-opening bar engaged at one end with the shank and at its other end adjoining the end of the hook portion, and an inturned hook on the bar projecting laterally into the eye opening 25 adapted to interlock with a part carried by the shank for the purpose described, the shank of the inturned hook being interposed between its interlocking part and the outer end of the eye to protect the latter from 30 contact with devices attached to the eye.
4. In a device of the character described, a hook part carried by a shank, and means for closing the space between the hook part and the shank including an outwardly- 35 opening closure having portions engaging adjacent portions of the hook and shank and an offset portion, in combination with a
- yieldable latching member in the eye over which the offset portion is adapted to ride in its closing movement and with which it 40 interlocks when closed to prevent opening movement.
5. In a device of the character described, an eye portion including a hook carried by a shank, and means for closing the space 45 between the end of the hook and the shank comprising a bar, and a substantially concealed latch adapted to engage a part on said bar to prevent opening thereof, said latch being releaseable only by the interposition of an extraneous tool, as the blade 50 of a penknife, to force the same from engagement with the bar, and to prevent accidental release of the latch by engagement with exterior objects in service.
6. A device of the character described comprising a hook part carried by a shank, and means for closing the space between the end of the hook part and the shank comprising an outwardly-opening bridging 60 member, and self-locking means operatively associated with said bridging member to prevent automatically engaging the same when closed to prevent unintentional opening thereof, the bridging member having 65 portions independently of the self-locking means, engaging the end of the hook part and the shank.

In testimony whereof I hereunto affix my signature in the presence of two witnesses. 70
